(57) **CLAIM**

The ornamental design for a monitor, as shown and described.

DESCRIPTION

FIG. 1 is a top, front, right side perspective view of a monitor, showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, rear, right side perspective view of the monitor of FIG. 1, shown in a condition of use; and,

FIG. 10 is a top, rear, right side perspective view thereof, shown in another condition of use.

The broken lines in the drawings depict portions of the monitor that form no part of the claimed design. The broken lines showing the desk stand in FIG. 9 and the floor stand in FIG. 10 depict environmental subject matter that forms no part of the claimed design.

1 Claim, 10 Drawing Sheets
